UNITED STATES PATENT OFFICE.

HAROLD BROWN, OF MOLINE, ILLINOIS, ASSIGNOR TO REYNOLDS ENGINEERING COMPANY, OF MOLINE, ILLINOIS, A CORPORATION OF ILLINOIS.

LAPPING-MACHINE.

1,295,962.

Specification of Letters Patent.

Patented Mar. 4, 1919.

Application filed May 24, 1918. Serial No. 236,269.

To all whom it may concern:

Be it known that I, HAROLD BROWN, a citizen of the United States, and a resident of Moline, in the county of Rock Island and

- 5 State of Illinois, have invented certain new and useful Improvements in Lapping-Machines, of which the following is a specification, reference being had to the accompanying drawings.
- 10 This invention relates to an improved grinding or lapping machine, adapted for automatically grinding shaft and other bearings to their seats. It has been the common practice in securing an accurate fit between the bearing brasses or bushings and their seats in connection with motor crank cases for a workman, after applying red lead or any other suitable medium to the surfaces of a bushing and its seat and noting
- 15 the points of contact, to scrape such places until a perfect fit is obtained. Such method is not only tedious but slow, and it is the object of my invention to provide means for rapidly and effectively doing such work and
- 20 doing it simultaneously in connection with a plurality of bearings. Briefly stated, I accomplish this object by providing an oscillating arbor having means for properly engaging each bushing and holding it forcibly
- 25 but yieldingly against its seat while the arbor is being oscillated, all as particularly described hereinafter. That which I believe to be new will be pointed out in the claims.

In the drawings:

- 30 Figure 1 is a front elevation of a machine embodying my improvements, a portion of a motor crank-case being shown in position on the bed of the machine, and the three bushings and their seats that are shown being in section;

Fig. 2 is an end elevation of the machine;

Fig. 3 is a vertical section, enlarged, at line 3—3 of Fig. 1;

Fig. 4 is a detail, being a perspective view 45 of one of the devices carried by the arbor for engaging the bushing while such bushing is being ground against its seat;

Fig. 5 is a detail, being a perspective view showing a portion of the oscillating arbor 50 with a flanged bushing-engaging device or holder in place on such arbor and in engagement with a flanged bushing such as shown at the left-hand end of the arbor in Fig. 1; and

Fig. 6 is a view similar to Fig. 5, but

showing an unflanged bushing as is the central one of the bushings in Fig. 1.

Referring to the several figures of the drawings,—

In Figs. 1 and 2 is shown a machine of the general lathe type, the frame thereof being indicated by 10, its supporting legs by 11, and its bed by 12. 13 indicates a work supporting table, which, as usual in machines of this type, is adjustable longitudinally and laterally of the bed. 14 and 15 indicate oppositely-disposed standards for supporting, respectively, the head stock 16 and tail stock 17, which members 16 and 17 are adjustable up and down by the turning 60 of the crank 18 and mechanism connected with the crank, which mechanism being well understood it is not necessary to here illustrate or describe. The head stock carries the usual live shaft 19 and the tail stock the 65 usual dead shaft 20, and between the pivot points of such two shafts is mounted an arbor 21, said arbor being made fast by a bracket or arm 22, as usual, to a head 23 secured upon the live shaft 19. Said shaft 70 19 instead of being continuously rotated as in the ordinary lathe is given a rapid oscillatory motion which is effected through the medium of an eccentric 24 mounted on a driving shaft 25 journaled in a rearward 75 extension of the standard 14. To the eccentric is adjustably secured a connecting bar 25^a which at its forward end is pivotally mounted upon a wrist pin 26 on the end of a crank 27 that is secured in any 80 suitable manner, but preferably adjustably, upon the outer end of the live shaft 19. The drive shaft 25 is driven by any suitable means. Preferably a three-step cone pulley is secured upon the shaft as a portion of the 85 driving means.

The arbor 21 is provided with as many separate devices as there are bushings to be ground. Each of the devices for engaging a bushing consists of a member, the outer face 100 of which is semi-cylindrical and of a size and shape to correspond to the concave inner face of a semi-cylindrical bushing. Such bushing-engaging member is indicated by 28. Projecting outwardly from each of its edges 105 is a flange 29 that projects over and bears against one of the edges of a bushing. As shown, these flanges 29 are in the form of short ears located centrally of the length of the member 28, but, of course, if desired, al- 110

though I do not deem it necessary, such flanges may be of greater length. As shown, the inner face of the bushing-engaging member 28 is not semi-cylindrical like its outer face, but is provided with a number of angularly disposed faces, the two side ones of which are parallel, such construction being given to it to adapt it to fit upon and be held securely to the arbor, which, at the point 5 where the holding device 28 is applied, is cut away to correspond. Thus it will be evident that when the holding member 28 is in place on the arbor it cannot have any independent movement with relation thereto either longitudinally or axially, as the parallel side walls formed on the arbor will prevent any tendency to axial movement and the shoulders formed at the ends of such arbor-walls will hold the device against end- 10 wise movement. I provide means, however, for positively securing the member 28 to the arbor and at the same time provide for regulating the degree of pressure with which the device will force the bushing to its seat. Referring to these means,—30 indicates a stem 15 extending through the arbor midway between the parallel straight sides that are cut in the arbor, as clearly shown in Figs. 5 and 6, which stem is screw-threaded into a hole 20 extending centrally through the bushing-holding device 28, the head of the stem being preferably countersunk in the arbor, as shown. 31 indicates a socket formed in the arbor around the stem, in which socket is located a coiled spring 32 that bears against 25 the holding member 28. With the arbor held in the machine in fixed position as in Fig. 1, it is evident that the pressure by which the bearing is forced against its seat can be 30 regulated by the turning of the stem, and at the same time, by virtue of the spring arrangement, have such pressure a yielding one. The head of the stem is notched to enable the desired adjustment to be made by 35 means of a screw-driver or other similar tool. 33 indicates a portion of a motor crank-case and 34 are semi-cylindrical seats 40 therein in each of which is adapted to rest a semi-cylindrical brass bushing 35. 45 In operation the device having the bushing or bearing seats—and which device has been herein referred to as a motor crank case—is secured in place properly upon the bed of the machine, and an arbor having bushing-engaging members that correspond in location to the said seats is then placed in position on the machine so that when lowered 50 the engaging members 28 will fit into their respective bushings that have been placed in the seats 34. After the arbor has been lowered by the usual manipulation of the mechanism connected with the head stock and tail stock, and the holding members 28 are snugly fitted within the semi-cylindrical bushings power is applied to the shaft 55 60 65

which, of course, through the connections between that shaft and the live shaft 19 will cause a continued rocking or oscillating movement to be applied to the arbor with a corresponding rocking or oscillating of the 70 bushings so that a very effective grinding between their outer surfaces and their respective seats will be accomplished—it being understood, of course, that oil and emery, as usual, will have been supplied between the 75 said surfaces. In Fig. 3 I have indicated by dotted lines approximately the extent which I deem desirable to rock the parts, but the degree of movement can, of course, be regulated by an adjustment of the connecting 80 rod 25^a.

While I have described my invention with particular reference to the grinding or lapping of crank case bearings for motors, it will be found equally effective in connection 85 with semi-cylindrical or split bushings for other uses. Of course, it will also be understood that different arbors will be required for different pieces of work so that an arbor may be employed having the holding members 90 28 spaced the right distance apart to correspond to the bearing seats in the particular piece of work being done.

By the use of my invention much time and labor can be saved over the old practice 95 of manually scraping down semi-cylindrical bearings or bushings, for not only is the work capable of being done more rapidly on each individual bushing, but as many bushings as may be desired may be operated 100 upon simultaneously.

What I claim as my invention and desire to secure by Letters Patent, is—

1. In a machine of the class described, the combination with an arbor and means for 105 oscillating it, of a device connected therewith for engaging a curved bearing member and rocking it in frictional engagement with its seat.

2. In a machine of the class described, the combination with an arbor and means for oscillating it, of a device connected therewith for yieldingly engaging a curved bearing member and rocking it in frictional engagement with its seat. 110

3. In a machine of the class described, the combination with an arbor and means for oscillating it, of a device carried thereby for bearing against the edges of a semi-cylindrical bushing when said bushing is resting 120 on its seat whereby said bushing will be ground against the seat during the oscillation of the arbor.

4. In a machine of the class described, the combination with an arbor, of a device having a semi-cylindrical outer face and oppositely-disposed lateral flanges for engaging respectively the inner face and the edges of a semi-cylindrical bushing when said bushing is resting on its seat, means for con- 125 130

necting said device with the arbor, and means for oscillating the arbor to grind the bushing against its seat.

5. In a machine of the class described, the combination with an arbor having two opposite parallel side walls, of a bushing-engaging member movably seated against said side walls and having laterally-extending flanges for engaging the edges of a bushing 10 when said bushing is on its seat, and means for oscillating the arbor to grind the bushing against said seat.

6. In a machine of the class described, the combination with an arbor having two opposite parallel side walls, of a bushing-engaging member movably seated against said side walls and having laterally-extending 15

flanges for engaging the edges of a bushing when said bushing is on its seat, means for movably securing said bearing-engaging 20 member and the arbor together, a spring tending to force said member away from said arbor, and means for oscillating the arbor to grind the bushing against said seat.

7. In a machine of the class described, the combination with an arbor, of a bushing-engaging member on said arbor, means for adjusting said member radially of the arbor, a spring interposed between the arbor and said member and tending to force said member outward, and means for oscillating the arbor and the said member. 25 30

HAROLD BROWN.
